UNITED STATES PATENT OFFICE.

JOHN A. TOPPING, OF BRONXVILLE, NEW YORK.

DESIGN FOR A ROOF.

Application filed August 10, 1927. Serial No. 23,037. Term of patent 14 years.

To all whom it may concern:

Be it known that I, JOHN A. TOPPING, a citizen of the United States, and residing in the village of Bronxville, in the county of Westchester and State of New York, have invented a new, original, and ornamental Design for a Roof, of which the following is the specification, reference being had to the accompanying drawings, forming a part thereof.

On the drawings:

Figure 1 is a plan view of a shingle, showing my design.

Figure 2 is a plan view of a roof composed of shingles as shown in Figure 1, showing my design.

I claim:

The ornamental design for a roof, as shown.

JOHN A. TOPPING
